(57) **CLAIM**

The ornamental design for a robot for cleaning, as shown and described.

DESCRIPTION

1. Robot for cleaning
- 1.1 : Perspective
- 1.2 : Front
- 1.3 : Back
- 1.4 : Left
- 1.5 : Top
- 1.6 : Bottom

The broken lines depict portions of the robot for cleaning that form no part of the claimed design; reproduction 1.1 is a front perspective view of the robot for cleaning; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof.

1 Claim, 6 Drawing Sheets
